CLAIM

The ornamental design for a surgical kit, as shown and described.

DESCRIPTION

The file of this patent contains at least one photograph executed in color. Copies of this patent with color photographs will be provided by the Office upon request and payment of the necessary fee.

FIG. 1 is a front perspective view of a surgical kit showing a first embodiment of my new design;

FIG. 2 is a front perspective view thereof;

FIG. 3 is a rear perspective view thereof;

FIG. 4 is a left side perspective view thereof;

FIG. 5 is a right side perspective view thereof;

FIG. 6 is a top perspective view thereof;

FIG. 7 is a bottom perspective view thereof;

FIG. 8 is a front perspective view of a surgical kit showing a second embodiment of my new design;

FIG. 9 is a front perspective view thereof;

FIG. 10 is a rear perspective view thereof;

FIG. 11 is a left side perspective view thereof;

FIG. 12 is a right side perspective view thereof;

FIG. 13 is a top perspective view thereof; and,

FIG. 14 is a bottom perspective view thereof.
